UNITED STATES PATENT OFFICE

MALCOLM HARD, OF FLUSHING, NEW YORK, ASSIGNOR TO THE SUPERHEATER COMPANY, OF NEW YORK, N. Y.

SUPERHEATER HEADER

Application filed July 7, 1928. Serial No. 291,102.

The present invention relates to headers for locomotive superheaters. The header for such a superheater is, according to common practice, located in the smokebox above the level of the flues. The superheater comprises in addition to the header a plurality of tubular units or elements extending into the flues or fire-tubes of the locomotive, the ends of these units being secured by bolts to the bottom of the header.

The headers in ordinary use are made of a high grade cast iron and the art of making them has advanced so far that failures are almost unheard of. For some reasons and under some conditions, however, it becomes desirable to make these headers of plate steel. The main advantage of a plate steel header over the cast headers referred to above is the matter of weight. A cast steel header could also probably be made materially lighter than a cast iron header but it has hitherto proved impractical to use cast steel on account of the difficulty encountered in casting. The art of welding has, however, progressed to such an extent by this time that such a header can be built up of rolled steel plates.

The most approved form of these headers is the so-called "thru-bolt type". By this expression is meant a type of header in which the heads of the bolts are on the upper side of the header, the bolts extending through proper openings in the header, and the nuts being on the under side. The present invention relates to this thru-bolt type of header and has for its object the provision of an improved form of such a header made of plate steel.

The header is illustrated on the drawings herewith in which Fig. 1 is a front elevation partly in section on line 1—1 of Fig. 2; Fig. 2 is a top view of a header, part of it in section on line 2—2 of Fig. 1; Fig. 3 is a sectional view on line 3—3 of Fig. 2, and Fig. 4 is a section on line 4—4 of Fig. 2.

In making a header according to my invention, I begin with a substantially rectangular sheet of steel 1 and bend it to form the rear chamber 2 and the front chamber 3. These chambers have their inner sides, which face each other, open at this stage. A series of

elongated openings 4—4 have been formed in the upper sheet in a position which will be clear from the drawings. Into these openings are next welded a corresponding number of flattened thimbles 5—5. At the points 6 these thimbles are in contact with the inner edges of the sheet 1.

Plates 8—8 are next welded in at alternate ends of the passages 9—9 between the thimbles. These plates are welded to the edges of the sheet 1, to the top plate and to neighboring thimbles. Next, blocks of steel 7—7 are welded in to fill up the space between the edges of the sheet 1 and neighboring thimbles. These blocks have openings 19—19 through them through which the superheater elements or units are to communicate with the interior of the header. The plates themselves are of considerably thicker gage than the remainder of the header. This is for the purpose of making it possible to provide suitable seats for the ends of the units.

The ends of the headers are closed by the plates 10—10 welded to the end edges of plate 1 and to the outer plates 7. A connection 11 is welded into a suitable opening cut into the rear chamber 2 to which connection the dry pipe is secured in the ordinary manner. Similarly two connections 12—12 are provided for the attachment of the steam pipes, 80 these connections being welded into suitable openings cut into the front chamber 3. The openings for these several connections are most conveniently made by means of a torch, although the sheet may if desired be suitably stamped out before it is bent into shape.

The attachment for the superheater units is illustrated in Fig. 1 where two superheater ends 13—13 are illustrated. These ends have enlarged heads 14—14 in accordance with the ordinary practice, which are pressed against the seats in the openings 8—8 by means of the clamp 15, washers 16—16 being interposed between the clamp and the enlarged heads 14—14. The clamp is pulled in the desired direction by means of the bolts 16^a extending through the thimble 5, the head 17 resting on the upper end of the thimble and the nut 18 being on the underside of the clamp. It will be understood that while only 100

one pair of unit ends and one bolt is shown, others lie in line with them. In the particular header shown, there will be four bolts through each thimble. This method of attaching the units represents standard practice and illustrates that the present header can be used with standard equipment.

It will be seen from the above description that by the method described a header is provided which will conform in its dimensions and arrangement for the superheater attachments exactly to the present standards. All the advantages of the thru-bolt type are present, and in addition the header is of substantially lighter structure and has all the advantages inherent in its being made of steel.

Obviously some changes can be introduced in practicing my invention without departing from its spirit.

I claim:

1. In a bi-chambered steel-plate header, a partition separating one chamber from the other, said partition comprising a series of open-ended flattened thimbles extending between and welded to opposite sides of said header and adapted to have bolts extend through them.

2. In a bi-chambered steel-plate header, a partition separating one chamber from the other, said partition comprising a series of open-ended alined parallel flattened thimbles extending between and welded to opposite sides of said header, and plates welded in closing the passages between said thimbles at alternate ends.

3. In a steel-plate header of the type described, the combination of a top, a bottom, a plurality of open-ended flattened alined parallel thimbles extending through and welded to said top and bottom, and plates with their edges welded to the top and bottom and to the thimbles in such a manner as to close the passages between the thimbles at alternate ends.

4. A steel-plate header comprising a unitary generally rectangular sheet with its opposite portions bent to form two elongated parallel chambers with their inner sides open, a plurality of spaced plates welded into each of said openings the spaces left in one opening lying opposite the plates of the other, open-ended flattened thimbles extending through said first plate and welded to opposite edges of said spaced plates, and a plurality of comparatively thick plates each filling a space between opposite edges of said first named plate and adjacent thimbles and welded thereto.

5. In a steel-plate header, the combination of a continuous sheet forming the top, back, and front of the header, a portion of the bottom adjacent to the front, and a portion of the bottom adjacent to the back; and means forming the remaining portion of the bot-

tom comprising a plurality of relatively thick small plates.

6. In a steel-plate header, the combination of a continuous sheet forming the top, back, and front of the header, a portion of the bottom adjacent to the front, and a portion of the bottom adjacent to the back; and means forming the remaining portion of the bottom comprising a plurality of relatively thick plates two of whose opposite edges are welded to the edges of the first-named plate; a plurality of open-ended flattened thimbles extending through and welded to the first-named plate and between said thick plates and welded to them; a plurality of plates with their edges welded into the openings between said thimbles at alternate ends; end plates welded to the end edges of said first named plate and to the outer thick plates; and connection means welded into said front and back.

7. The method of making a plate steel header, comprising the steps of bending a generally rectangular plate to form two parallel spaced chambers with their juxtaposed inner sides open, providing the plate with a plurality of slots, welding a flattened thimble into each slot, welding steel plates in to close the passages between the thimbles at alternate ends, welding a relatively thick steel plate in each opening between the opposite edges of the rectangular plate and the several thimbles, and providing suitable connections to the two chambers.

8. The method of making a plate steel header, comprising the steps of providing a generally rectangular steel plate with a plurality of parallel alined slots, spaced from the edges of the plate; and bending the portions between the ends of the slots and the edges of the plate to form two chambers on the same side of the plate and parallel to each other.

9. The method of making a plate steel header comprising the steps of providing a generally rectangular steel plate with a plurality of parallel alined slots, welding the ends of open-ended flattened thimbles into the slots, and welding steel blocks between the opposite ends of the thimbles so that the blocks lie in a plane parallel to the sheet.
